UNITED STATES PATENT OFFICE.

SAMUEL A. BENNER, OF PITTSBURGH, PENNSYLVANIA.

BUILT-UP TRUCK SIDE FRAME.

1,283,049.

Specification of Letters Patent. Patented Oct. 29, 1918.

Application filed November 13, 1913, Serial No. 800,878. Renewed March 17, 1917. Serial No. 155,619.

To all whom it may concern:

Be it known that I, SAMUEL A. BENNER, a citizen of the United States, and resident of Pittsburgh, in the county of Allegheny and State of Pennsylvania, have invented a new and useful Improvement in Built-Up Truck Side Frames; and I do hereby declare the following to be a full, clear, and exact description thereof.

10 My invention relates to improvements in truck side frames and is particularly concerned with the construction of a side frame in which all parts including the pedestal are formed of rolled sections of steel. The object of the invention is the production of a side frame of great strength in proportion to its weight, one in which the parts may be very easily and strongly assembled. A further object is to secure a very material reduction 20 in the cost of manufacture, both in the production of the parts of the frame, and also in the labor of assembling.

With these objects in view the invention consists in constructions and arrangements 25 of parts, preferred embodiments of which are illustrated in the accompanying drawings, in which Figure 1 is a side elevation of a side frame embodying the improvements; Fig. 2 is a longitudinal vertical section of said frame; Fig. 3 is a plan view; Fig. 4 is a sectional view on the line 4—4, Fig. 1; Fig. 5 is a sectional view on the line 5—5 Fig. 1; Fig. 6 is a fragmentary perspective view illustrating forms of rolled 30 sections which may be employed as the compression and tension members of the frame, respectively. Figs. 7, 8, 9, and 10 are views similar to Fig. 6 illustrating modified forms of sections which may be so employed. Figs. 35 40 11 and 12 illustrate respectively compression and tension members of the same general shape in which parts of the compression member are cut away to permit the proper assembling of the two members of the frame. Fig. 45 13 illustrates a further modification which permits a change in the form of the truck pedestal hereinafter described.

In one of the preferred forms of the invention in so far as I am able to determine 50 the same at this time, the rolled sections employed as the compression and tension members respectively are of the form shown in Fig. 10 in which the compression member consists of a section of flanged channel 55 form, having the web 1, the side walls 2, 2, and the lateral flanges 3, 3. Such a rolled

section may be produced in a manner well known to those skilled in the art of metal rolling. The tension member consists of a rolled section having the base web 4 extending laterally into the flanges 5, 5, the side walls 6, 6, and the upper flanges 7, 7. The side frame illustrated in Figs. 1 to 5 inclusive, is constructed of sections such as those just described and shown in Fig. 10. It will be noticed from Fig. 10 that the compression member consists of the simple channel sections 1—2—2, of a width to fit snugly within the channel 4—6—6 of the tension member and the flanges 3—3 of the compression section are riveted to the flanges 7, 7 of the tension member as at 8. The compression and tension members are bent to the form shown in Figs. 1 and 2 and are thus spaced apart to receive the pedestal. This 75 pedestal as shown in Figs. 1, 2, 4 and 5 is formed of a simple rolled channel section having the base web 9 and the flanges 10, 10, and is bent into the pedestal section as illustrated in Figs. 1 and 2. This channeled pedestal section is of such width that its flanges 10—10 fit exactly within the side walls 6—6 of the tension member as illustrated in Fig. 4 and said flanges 10 and the side walls 6 are riveted together as at 11. Inasmuch as 80 the pedestal section in the form of the invention now being described is of the same width as the compression section, the flanges 10—10 at the upper side of the pedestal section are expanded as shown at 12—12 so that 90 said flanges may closely embrace the side walls 2 of the compression member and are secured thereto by rivets 10'. Referring again to Fig. 4 it will be seen that the flanges 7—7 of the tension member and the 95 bottom web 9 of the pedestal, together form a flat face or foundation for the reception of the spring base plank 13 which extends from one side frame to the other in the usual manner and this spring plank as will be seen 100 from Figs. 1 and 2 may be formed of a rolled section having the flanges 14—14, which not only form proper housings for the lower ends of the bolster springs, but also serve to strengthen the spring support. 105

From the peculiar construction of the compression and tension sections as above described, it will be seen that an especially strong structure of side frame is produced and the strength is properly distributed to 110 resist the various strains brought to bear on the frame. For example, the box like

structure of the tension member formed by said member and the lower portion of the pedestal section as shown in Fig. 4 provides an especially strong structure for receiving the thrust of the bolster springs 15. Again the broad web 4 with its flanges 5—5 of the tension member forms a strong construction for the reception of the pillar bolts 16 of the journal box 17 and for the journal boxes 10 themselves and this journal box bearing is reinforced by the base web 1 of the compression member or section.

Considering the compression and tension members in their simplest aspect, it will be seen that they consist essentially of continuous channel members, the ends of one fitting within the ends of the other, thus affording the most powerful construction to resist lateral as well as vertical strains. It is apparent, therefore, that in its simplest aspect, this invention contemplates the use of simple channel sections for the compression and tension members. These simple channel members may be developed by additions of various arrangements and constructions of flanges for reinforcement and for providing proper bearings for the bolster springs and for the journal boxes.

As illustrating the various forms which the compression and tension members or sections may take, reference is made to Figs. 5 to 9 inclusive and 11, 12, and 13. Fig. 10, as before stated, illustrates a development of these sections which is employed in the preferred form of the invention, illustrated in Figs. 1 to 5 inclusive. In Fig. 6 the compression member is formed from a channel section having the bottom web 18 and the side walls 19, 19. The tension member comprises the bottom web 20 and the side walls 21, 21. In Fig. 7 the compression member may be the same as that shown in Fig. 6 and the tension member also the same as illustrated in Fig. 6 with the addition of the flanges 22—22. In Fig. 8 the tension member is that same as that shown in Fig. 7, while the compression member is likewise the same with the addition of the flanges 23. In Fig. 9 the compression member is like that in Fig. 7 and the tension member like the form Fig. 10. In Figs. 11 and 12, the two sections which form the compression and tension members are of the same form, the tension member consisting of a section similar to that shown in Fig. 10 and having the web 4, the base flanges 5—5 and the upper flanges 7—7. The compression member comprises a channel portion consisting of the web 24, the side walls 25, 25, and the upper flanges 26, 26. As shown in Fig. 11 which illustrates the compression member, the web 4 is expanded into flanges 27, 27, which are cut back adjacent the ends of the section to the point 27' to permit the channel portion 24, 25, 25 to fit or nest within the

channel shaped ends of the tension member. In the construction illustrated in Fig. 13 it will be seen that the channel portion 28, 28'—28' may be somewhat narrower than the space between the side walls 29—29 of the channel portion of the tension member, so that the side flanges 10 of the pedestal channel section may in their normal position embrace the side walls 28 of the compression member and likewise fit snugly within said walls 29 of the tension member, thus avoiding the necessity of expanding flanges along the upper side of the pedestal member.

By reason of the fact that the compression and tension members and the pedestal section may be riveted together through their respective flanges or side walls, it will be seen that all of the rivets of the structure may be in shear instead of in tension, thereby securing the greatest possible strength in the junctures of these parts.

From the manner of forming this compression section and afterward cutting away the same as just described, it will be seen that in this form of the invention also, we retain the simple channel shape of the section at the ends which engage or are nested within the ends of the tension member, and moreover, these channel shaped ends of the compression member may fit snugly within the side walls of the tension member while at the same time the depending flanges at the center of the compression member may be at a less distance apart and thus engage within the flanges of the pedestal without expanding the pedestal flanges at the upper side.

While I have herein described preferred embodiments of my invention, and have illustrated possible modifications not only of the sections from which the compression and tension members respectively may be formed, but also differences in relative arrangement of the parts, it is to be understood that the invention may be still further modified within the scope of the appended claims.

What I claim is:

1. A truck side frame having its compression and tension members formed of rolled upwardly opening channel shaped sections, one of which sections is narrower than the other, so that the channel shaped ends of one member nest within the corresponding channel shaped ends of the other, and a pedestal formed entirely of a rolled channel whose web forms the inner walls of the pedestal and whose flanges are closely adjacent and secured to the side walls of the channel shaped compression and tension members respectively.

2. A truck side frame having its compression and tension members formed of rolled channel shaped sections one of which sections is narrower than the other so that the

channel shaped ends of one member nest within the corresponding channel shaped ends of the other and a pedestal formed entirely of a rolled channel whose web forms

5 the inner walls of the pedestal, arranged to fit within the side walls of the channel shaped tension member at the lower side of said pedestal and to embrace the side walls of the channel shaped compression member
10 at the upper side of said pedestal.

3. A truck side frame having its compression and tension members formed of rolled channel shaped sections, one of which sections is narrower than the other, so that the
15 channel shaped ends of one member can be inclosed between the side walls of the channel shaped ends of the other member and spaced slightly away therefrom, and a pedestal formed entirely of a channel shaped section
20 whose web forms the inner walls of the pedestal and whose flanges embrace the side walls of the narrower channel frame section and are inclosed within the side walls of the wider channel frame section, said pedestal
25 channel being of the same width throughout its circumference.

4. A truck side frame having its compression and tension members formed of rolled channel shaped sections one of which sections is narrower than the other so that the
30 channel shaped ends of one member will fit within the corresponding channel shaped ends of the other, the side walls of the tension member being flanged laterally to
35 strengthen the same and to provide in conjunction with the pedestal a broad bearing for the bolster springs.

5. A truck side frame having its compression and tension members formed of rolled
40 channel shaped sections one of which sections is narrower than the other so that the channel shaped ends of one member will fit within the corresponding channel shaped ends of the other, the side walls of the tension member being flanged laterally to strengthen the same and to provide in conjunction with the pedestal a broad bearing for the bolster springs, and the side walls of
45 the compression member being likewise flanged laterally to strengthen the same and to provide bearing faces contacting with the lateral flanges of the tension member to facilitate the securing of said members together.

55 6. A truck side frame having its compression and tension members formed of rolled channel shaped sections one of which sections is narrower than the other, so that the channel shaped ends of one member will nest within the corresponding shaped ends of the other, the side walls of the tension member being flanged laterally to strengthen the same and to provide in conjunction with the pedestal a broad bearing for the bolster
60 springs, and the base web of the tension
65

member being laterally extended to form further longitudinal and lateral strengthening members therefor.

7. A truck side frame having its compression and tension members formed of rolled
70 channel shaped sections, one of which sections is narrower than the other so that the channel shaped ends of one member will nest within the corresponding channel shaped ends of the other, the side walls of either or
75 both of said members being laterally flanged to form lateral and longitudinal strengthening members therefor.

8. A truck side frame having its compression and tension members formed of rolled
80 channel shaped sections, one of which sections is narrower than the other, so that the channel shaped ends of one member will nest within the corresponding channel shaped ends of the other, the side walls of both of
85 said members being laterally flanged to form lateral and longitudinal strengthening members therefor, the flanges on the side walls of the compression member being adapted to form securing portions in contact with the
90 corresponding flanges of the tension member and to form longitudinal and lateral strengthening portions for said compression member.

9. A truck side frame having its compression and tension members formed of rolled
95 channel shaped sections, one of which sections is narrower than the other so that the channel shaped ends of one member will nest within the corresponding channel
100 shaped ends of the other, the side walls of both of said members being laterally flanged to form lateral and longitudinal strengthening members therefor, the flanges on the side walls of the compression member being
105 adapted to form securing portions in contact with the corresponding flanges of the tension member, and to form longitudinal and lateral strengthening portions for said compression member, the web of said compression member being also extended to form lateral and longitudinal strengthening flanges, said flanges being cut off adjacent the ends of said member to permit the channel shaped end portions of said compression member to be nested within the channel shaped portions of the tension member.

10. A truck side frame having its compression and tension members formed of rolled
120 channel shaped sections one of which sections is narrower than the other so that the channel shaped ends of one member will nest within the corresponding channel shaped ends of the other, and a pedestal formed of a rolled channel section whose
125 web forms the inner walls of the pedestal and having its side flanges arranged closely adjacent and secured to the side walls of the channel shaped compression and tension members respectively, the lower side of the
130

- pedestal section forming with the portion of the tension member engaged thereby a box-like member to receive the thrust of the bolster springs.
5. 11. A truck side frame having its compression and tension members formed of rolled channel shaped sections one of which sections is narrower than the other so that the channel shaped ends of one member will 10 nest within the corresponding channel shaped ends of the other, and a pedestal formed of a rolled channel section whose web forms the inner walls of the pedestal and having its side flanges arranged closely 15 adjacent and secured to the side walls of the channel shaped compression and tension members, respectively, and a spring base plank formed of a rolled channel shaped section whose ends are adapted to rest within 20 the lower portions of the pedestal on the opposite truck frames.
12. A truck side frame having its compression and tension members formed of rolled channel shaped sections one of which sections is narrower than the other, so that the channel shaped ends of one member nest 25 within the corresponding channel shaped ends of the other, either one or both of said channel shaped sections having lateral 30 flanges at the edges of the side walls thereof to form reinforcements.
13. A truck side frame having its compression and tension members formed of rolled channel shaped sections one of which sections is narrower than the other, so that the channel shaped ends of one member nest within the corresponding channel shaped ends of the other, and with the web of either or both of said channel shaped sections extended laterally to form reinforcements.
14. A truck side frame having its compression member formed of rolled differential channel shaped section, having the side walls of the lower channel cut off at 45 the ends of said section and having the side walls of the upper channel cut off at the center portion, and a tension member formed of a rolled channel shaped section wider than the upper channel shaped portion of 50 the compression member, so that the ends of said compression member may nest within the corresponding channel shaped ends of the tension member, and a pedestal formed of a rolled channel shaped section 55 whose web forms the inner wall of the pedestal and whose flanges fit within the side walls of the channel shaped tension member and embrace the side walls of the lower channel portion of the compression member.
- 60 15. A truck side frame having its compression member formed of a roller differential channel shaped section in which the
- side walls of the lower channel portion are inset from the edges of said section, a tension member formed of a rolled channel shaped section, the flanges of the lower channel of the compression member being cut away adjacent the ends thereof to permit the upper channel portion of said compression member to nest within the channel shaped portion of the tension member, the central portion of the flanges of the upper channel of said compression member being cut away so that the central portions of 75 the flanges of the lower channel portion of said compression member form a downwardly opening channel and a pedestal 80 formed of rolled channel shaped section of uniform width throughout the circumference of said pedestal and of such width that the side walls or flanges of said pedestal section fit within the side walls of the channel shaped portion of the tension member and embrace the side walls of the channel shaped central portion of the compression member.
16. A truck side frame having its compression member formed of a rolled differential channel shaped section in which the 90 side walls of the lower channel portion are inset from the edges of said section, a tension member formed of a rolled channel shaped section, the flanges of the lower channel of the compression member being 95 cut away adjacent the ends thereof to permit the upper channel portion of said compression member to nest within the channel shaped portion of the tension member, the central portion of the flanges of the upper channel of said compression member being cut away so that the central portions of the flanges of the lower channel portion of said compression member form a downwardly opening channel and a pedestal 100 formed of rolled channel shaped section of uniform width throughout the circumference of said pedestal and of such width that the side walls or flanges of said pedestal section fit within the side walls of the channel shaped portion of the tension member and embrace the side walls of the channel shaped central portion of the compression member, the portions of the web of the compression member extending laterally beyond 105 the side walls of the lower channel portion thereof at the center, forming shoulders to receive vertical thrust of the pedestal section.
- 110 In testimony whereof, I the said SAMUEL A. BENNER have hereunto set my hand.
